INKING MECHANISM FOR CYLINDER
PRINTING PRESSES

John Haspert, Tampa, Fla.

Application February 12, 1948, Serial No. 7,788

9 Claims. (Cl. 101—352)

1

The present invention relates to improvements in inking mechanisms for cylinder printing presses and aims generally to improve such mechanisms, particularly for cylinder presses adapted for multicolor printing.

One of the objects of the invention is to provide a plurality of inking units for a multiple cylinder printing press in which the inking units may be simultaneously raised and lowered into and out of inking contact or engagement with the printing cylinders.

A further object of the invention is to provide an inking mechanism unit that may readily and quickly be removed from the press for cleaning and replacement.

A further object of the invention is to provide an improved inking mechanism unit having an ink reservoir and fountain roll, and a plurality of transfer and form rolls so related that a continuous supply of ink is maintained from the reservoir to the form rolls.

A further object of the invention is to provide a roll type inking mechanism unit having a fountain roll and doctor blade with improved means for adjusting and regulating the ink taken up by the fountain roll.

A further object of the invention is to provide a roll type inking mechanism unit having improved means for adjusting the pressure or squeeze between adjacent contacting rolls, and thus regulate the transfer of ink to the form rolls.

A further object of the invention is to provide an improved roll type inking mechanism unit having provision for readily removing a plurality of the rolls as a group for cleaning.

A further object of the invention is the provision of an improved roll type inking mechanism unit having a plurality of rider rolls movably supported on a frame so as to permit ready removal thereof from the form rolls.

A further object of the invention is to provide an improved roll type inking mechanism unit having provision for readily releasing the pressure between the rolls when the unit is out of use without the necessity of wholly removing the rolls from the unit.

Other aims and objects of the invention will be apparent to persons skilled in the art by reference to the accompanying drawings and annexed detailed description illustrating and describing one preferred embodiment of the invention.

In the drawings—

Fig. 1 is a diagrammatic side elevation of a

2

portion of a multiple cylinder printing press suitable for multicolor printing and illustrating a plurality of inking units therefor;

Fig. 2 is a skeleton end elevation of the inking mechanism and supporting platform and the mechanism for raising and lowering it as viewed from the right hand end of Fig. 1, the left hand linkage of Fig. 2 being shown to position the inking platform in lowered position and the right hand linkage to elevate the platform;

Fig. 3 is a plan view of the inking mechanism unit embodying the present invention;

Fig. 4 is an end elevation as viewed from the right hand end shown in Fig. 3;

Fig. 5 is an end elevation of the inking mechanism unit as viewed from the left or drive end thereof, as viewed from Fig. 3;

Fig. 6 is a front elevation of the inking mechanism unit shown in Fig. 3;

Fig. 7 is a vertical sectional view through the roll adjusting mechanism as taken on the line 7—7 of Fig. 4;

Fig. 8 is a vertical sectional view through the doctor blade adjusting mechanism as taken on the line 8—8 of Fig. 4;

Fig. 9 is a horizontal sectional view through the doctor blade adjusting mechanism as taken on the line 9—9 of Fig. 4;

Fig. 10 is a transverse sectional view through the vibrator roll actuating mechanism as taken on the line 10—10 of Fig. 4;

Fig. 11 is a transverse sectional view as taken on the line 11—11 of Fig. 6;

Fig. 12 is a transverse sectional view through the inking mechanism as taken on the line 12—12 of Fig. 3; and

Fig. 13 is a transverse sectional view through the carriage for the transfer roll, a vibrator roll and form roll as taken on the line 13—13 of Fig. 6.

Referring to the drawings, the inking mechanism of the present invention is particularly adaptable for use in a multiple cylinder printing press having a plurality of laterally spaced horizontally disposed printing cylinders 1, suitably supported on a supporting arm 2 mounted on a base 3, such for example as disclosed in my prior co-pending application Serial No. 646,402, filed February 8, 1946, now U. S. Patent No. 2,606,493.

The printing mechanism advantageously comprises a platform 10 movably supported on guide posts 11 extending above the base 3 so as to be vertically movable beneath the printing cylinders. Suitable means for raising and lowering the platform may comprise pairs of toggle links

Fig. 1 is a diagrammatic side elevation of a

55

12 at opposite ends of the platform, each toggle having an end pivotally connected to a fixed part, as at 12^a, to an upstanding bracket 13 on the platform and to a nut 14. The nuts 14 are oppositely threaded on a shaft 15 journalled in bearings 16 on the base 3 and adapted to be rotated by miter gearing 17 on an actuating shaft 18 extending lengthwise of the base 3 below the platform 10. The threaded portions of the shaft 15 are oppositely threaded so that the respective nuts 14 are simultaneously moved toward and away from the center position as will be apparent. Actuation of the shaft 18 rotates the shaft 15 by means of the miter gearing to move the nuts 14 on the shaft 15 transversely in opposite directions toward and from the center. As the nuts move away from the center position, the links 12 are moved to a more perpendicular position, thus raising the platform 10 toward the printing cylinders 1, as shown in the right hand side of Fig. 2, and as the nuts 14 are moved inwardly, the platform is lowered toward the base as shown in the left hand side of Fig. 2.

The platform 10 is provided with a plurality of inking mechanism unit supports, one for each of the printing cylinders, and advantageously these supports comprise a machined surface 20 to which is secured a machined guide block 21 having a dovetailed groove 22 therein and which block may be secured to the machined surface 20 of the platform by hold-down screws or the like (not shown). As will be apparent, the blocks 21 may be assembled on the machined surface 20 with shims or other devices to insure accurate leveling of the blocks in a horizontal plane, and thus permit the upper surface of the form rolls of the inking mechanisms to be disposed in a common horizontal plane so that the form rolls will contact the printing cylinders under like pressure.

The inking mechanism unit of the present invention comprises a housing 25 for holding a supply of ink as well as housing a plurality of rolls, including a form roll, for transferring the ink to the printing cylinder. The base of the housing is formed with a depending dovetailed rib or key 26 accurately machined to fit in the dovetailed groove 22 of the blocks 21 so as to accurately be positioned on the platform. The keys 26 slidably fit in the dovetailed grooves 22 of the blocks 21, permitting the whole inking mechanism to be removed laterally as a unit from the platform 10 of the machine for replacement or cleaning.

The housing 25 is provided with a longitudinally disposed partition 27 which may terminate short of the bottom of the reservoir (see Fig. 12) to permit the flow of ink from a reservoir section 28 to a roll housing section 29 in which is positioned a fountain roll and doctor blade, transfer rolls, vibrator rolls and a form roll for transferring and uniformly spreading the ink from the reservoir to the form roll as is well understood in the art.

The fountain roll 30 is fixedly mounted in the lower portion of the housing section 29, being secured to a shaft 31 extending through the ends of the housing (see Fig. 10) and preferably consists of a smooth surfaced metal roll of a length corresponding substantially to the length of the form roll which contacts the printing cylinder. Desirably, the fountain roll 30 may be a copper or brass roll having a cadmium or chromium plated surface to provide a smooth surfaced finish. A doctor blade 32 (see Figs. 9, 10 and 12)

may be mounted upon a rod 33 journalled in bearings 34 in the ends of the housing 25 and having a longitudinal groove 35 for receiving a looped portion of the doctor blade which may be retained in the groove by a retaining key or rod 36. The blade 32 has an outwardly turned end portion 32^a and is preferably formed of or fitted with a bearing surface of softer material than the fountain roll with which it engages.

10 The doctor blade rod 33 may be suitably actuated to bring the end 32^a of the blade toward and from the surface of the fountain roll 30 to vary the amount of ink picked up by the fountain roll 30. One suitable mechanism for actuating the doctor blade may comprise mechanism for oscillating or rocking the rod 33. This advantageously may be accomplished by means of a head 37 secured to the end of the rod outside of the housing 25 and adapted to be moved by push rods 38 and 39, each engaging the head 37 above and below the center of the rod 33, respectively. The push rods 38 and 39 may be slidably mounted in a bracket 40 and each is provided with a worm gear 41 in mesh with a worm 42 on a shaft 43 having an adjusting knob 44. Rotation of the knob in one direction will transmit motion simultaneously to the push rods 38, 39 to move them in opposite directions so that the doctor rod 33 may be rocked optionally in either direction to move the doctor blade 32 toward or away from the fountain roll 30.

20 The outer terminal edge of the doctor blade 32 is preferably divided into sections as by V-shaped notches 45 at spaced intervals throughout its length (see Fig. 10), and each of these sections is engaged by the end of an adjusting screw 46 threadedly mounted in a part of the housing 25, as for example, of the partition 27. By means of the adjusting screws 46 the selective portions of the doctor blade may be adjusted to bear more tightly or loosely against the fountain roll to compensate for irregularities in the roll to provide a uniform spread of ink thereon or to cut down or close off sections of the roll almost completely as may be desired.

25 Mounted in the roll portion 29 of the housing 25 and above the fountain roll 30 are a rubber covered transfer roll 50, a pair of metal surfaced vibrator rolls 51, 52 and a rubber form roll 53 for transferring ink from the surface of the fountain roll to the printing cylinder of the printing press. One of these rolls, for example, the vibrator roll 52, may be rotated in fixed bearings in the ends of the housing 25, and the other rolls, namely the transfer roll 50, the vibrator 51, and the form roll 53, are preferably mounted in a carriage movable as a unit relative to the housing 25. For this purpose the rolls 50, 51 and 53 may be journaled in end brackets 54 at opposite ends of the housing (see Figs. 3, 4, 5, 6 and 13), each having a laterally extending guide pin 55 adapted to be slidably fitted in the bearings 56 on the end frames of the housing 25. By sliding the pin 55 from the bearings 56 of the housing end plates, the brackets 54 and connecting rolls 50, 51 and 53 may be moved laterally as a unit from the housing, vibrator roll 52 and fountain roll 30.

30 Means in the form of an adjusting mechanism are provided for adjusting the position of the bracket 54 and assembled rolls 50, 51 and 53, relative to the housing 25, fountain roll 30 and vibrator roll 52 so as to effect the desired pressure or squeeze between the several contacting rolls and thus regulate to a desired degree the

thickness of the ink film transferred to the form roll 53. In the illustrated embodiment of the invention the above adjusting means may advantageously comprise a shaft 60 mounted in the end walls of the housing and preferably above the reservoir compartment, and provided adjacent its opposite ends with suitable gearing 61 for transmitting rotary motion to a shaft 62 at right angles thereto and preferably mounted in a bearing 63. The gearing 61 is herein illustrated as co-acting spiral gears which are suitable for the purpose described. The shaft 62 has a threaded connection with the roll bracket 54 and preferably this is effected by threading the end of the shaft to engage in a threaded bore 64 in the lower portion of the bracket 54. Thus, the shaft 62 may be rotated, as by means of the knob 65, shaft 60 and gears 61 to rotate the threaded end thereof in the bore 64 of the bracket, thereby effecting an adjustment of the bracket and rolls 50, 51 and 53 carried thereby laterally with reference to the fixedly mounted rolls 30 and 52.

The vibrator roll 51 is mounted on a shaft 56 (Fig. 13) journalled in releasable bearings between the forward end of the brackets 54 and a link 67 pivoted as at 68 to the brackets 54 and normally held in closed position by a clamping plate 69 and screw 70. When the clamping plate 69 is tightened to hold the link 67 in closed position, the vibrator roll shaft is properly positioned in the carriage to insure proper contact between the vibrator roll 51 and the transfer and form rolls 50 and 53, respectively. Loosening the clamping plates 69 permits the link 67 to fall away from the carriage to permit the roll 51 to be positioned out of contact with the rolls 50 and 53.

The above described mountings for the transfer roll 50, the vibration roll 51 and the form roll 53 are of particular advantage in connection with relatively small multi-color presses of the type disclosed in my copending application Serial No. 646,402, filed February 8, 1946, now U. S. Patent No. 2,606,493, aforesaid. When the press is idle for substantial periods of time, as for example overnight, the pressure or squeeze between the several rolls may be released simply by operation of the knob 65 to move the carriage 54 and the rolls 50, 51 and 53 carried thereby away from the fixedly mounted rolls 30 and 52. This avoids damage to the rubber covered rolls 50 and 53 which rapidly deform if maintained under pressure when not in use. As will be apparent, the vibrator roll 51 may be released from pressure contact with the rubber covered rolls 50 and 53 by releasing the clamping screw 70 and plate 69, permitting separation of the link 67 from the bracket 54.

The vibrator rolls 51, 52 are preferably reciprocated longitudinally so as to spread ink properly over the form roll 53. Suitable means for reciprocating the rolls 51, 52 is provided, and preferably is supported wholly by the housing 25 so as to be movable with the rolls and housing as a unit.

In the illustrated embodiment (see Figs. 3, 6 and 11), the actuating means for the vibrating rolls comprises a plate member 71 secured to the forward wall of the housing and having journalled therein a shaft 72 carrying a worm 73 meshing with a worm gear 74 connected to a crank 75, the pin 76 of which works in a slotted portion 77 of a lever 78 pivoted as at 79 to the plate 71. The lever 78 has a pivoted extension 80 having an end portion working in

a slotted end 81 of an actuating lever 82 pivotally mounted as at 83 on a fixed part 84 of the housing 25. The actuating lever 82 has pins 85 fitting in grooved ends 51^a and 52^a of the rolls 51 and 52 whereby longitudinal movement of the rolls is effected, while permitting rotation thereof relative to the lever 82. The worm gear 74 and the crank 75 are rotated by means of the worm 73 on the shaft 72 the latter in turn being rotated by gearing connections 86 in mesh with a pinion 87 on the fountain roll shaft 31. Thus the crank 75 of the vibrating mechanism is driven from shaft 72 and synchronously with the fountain roll 30 to oscillate the lever extension 80 in the slotted portion of the actuating lever. The actuating lever 82 oscillates in turn about its pivot 83, being pivoted to the vibrating rolls 51 and 52 to reciprocate them in opposite directions.

The ink thus transferred to the form roll 53 is properly conditioned for transfer to the printing image of the printing cylinder by means of rider rolls 90, which preferably are of relatively soft material, for example rubber. These rolls 90 are preferably idle rolls driven by frictional contact with the form roll and are journalled at their opposite ends to the bracket members 91 pivoted at one end to the housing 25, preferably at the upper end of the reservoir portion 28. When the unit is in operation, the rolls 90 are in contact with the form roll as shown in Fig. 12. When the unit is not in position in the press, the rider rolls 90 may be released from pressure engagement with the form rolls as shown in full lines in Figs. 4 and 5, or may be swung upwardly and away from the form roll, as indicated in dotted lines, so as to relieve the soft surface thereof from pressure which is liable to result in distortion of the true cylindrical form of the roll.

The rolls 30, 50, 51, 52 and 53 are advantageously positively driven by means of intermeshing spur gears 30', 50', 51' and 53' fixed to their respective roll shafts, as illustrated in Fig. 6, and may receive power by means of a gear 95 on the form roll shaft which is adapted to mesh with the driving pinion 96 coupled with the printing cylinder (see Fig. 1) when the inking unit is in place in the machine.

The supply of ink from the reservoir compartment 28 of the housing 25 of the fountain roll 30 will vary somewhat depending upon the viscosity of the ink and the speed at which the press is operated. Where inks of relatively high viscosity are used at relatively high production speeds of the press, it may be desirable to assist the flow of ink from the reservoir to a point adjacent the fountain roll by means of an impeller or agitator device. One suitable form of agitator mechanism for this purpose comprises an agitator bar 97 disposed longitudinally of the reservoir 28 adjacent the bottom thereof and adapted to be oscillated towards and from a communicating passage between the reservoir and roll housing section 29, preferably below the partition 27. Desirably, the agitator may have an upstanding arm 98 provided with a bushing 99 journalled on the shaft 60 and provided with a pivoted link 100 adapted to extend outwardly over the end of the housing 25 to receive a slotted end of a crank arm 101 driven from one of the roll driving gears, for example the driving gear 30' for the form roll 30.

The link 100 of the agitator is advantageously pivoted to the bushing 99 so as to be swung inwardly and downwardly back to the partition 27.

to permit the rider rolls being moved into and out of position with respect to the form roll as shown in Figs. 4 and 5.

From the above description it will be apparent that I have provided a simple improved compact inking unit for printing presses particularly of the roll type, in which the unit may be inserted in and removed from the press by slidably engaging or disengaging the rib 26 in the groove 22 of the platform. When the invention is embodied in a multi-color press, and the several inking mechanisms are positioned on the platform 10, they may be simultaneously raised and lowered into and out of engagement with their respective printing members 1 simply by rotating the shaft 18 in the proper direction.

A machine such as is illustrated diagrammatically in Fig. 1 may advantageously be used for the printing of small articles in multi-colors, for example, labels, wrappers and the like job work. With such work the press may be idle for substantial periods of time, in which case it is desirable to remove the printing mechanism for cleaning and storage. As will be apparent, each printing unit is readily removable laterally from the platform 10 by simply sliding the housing from the grooved block 21.

In storing the inking mechanism when not in use, it is desirable that the rubber covered rolls be out of pressure engagement with other rolls, to avoid damage to the pliable surface. With the present unit this may be accomplished by raising the bracket 91 to release the rider rolls from engagement with the form roll 53. The carriage 54, carrying the form roll 53, vibrator roll 51 and transfer roll 50 may be then moved transversely of the housing by rotation of the knob 65 to separate these rolls from the fountain roll 39 and vibrator roll 52. The vibrator roll 51 may be moved away from the form roll 53 and transfer roll 50 by releasing the screw 70 and clamp 69, permitting the link 57 carrying the vibrator roll shaft 66 to fall away from the carriage 54. Furthermore, the adjusting mechanism for the carriage permits the operator to obtain the desired squeeze between the rolls when setting up the press for use.

Although I have illustrated and described a preferred embodiment of the invention, I do not intend to be restricted thereto as the invention includes equivalent means as may be within the scope of the appended claims.

I claim:

1. In a printing press in combination with a printing roll, an inking mechanism platform provided with a horizontally disposed guideway below and parallel to said roll, an inking mechanism unit comprising a housing providing an ink reservoir and transfer roll mounting, said housing having a guide fitting said guideway whereby said unit may be removed laterally from said platform and means for moving said platform vertically to carry said inking mechanism into and out of inking position.

2. An inking mechanism unit for roll type printing presses comprising a housing providing a roll compartment and an ink reservoir in communication therewith, a fountain roll rotatably mounted in said housing and extending into said roll compartment, a doctor blade bearing on the surface of said fountain roll, the outer terminal edge of said doctor blade being divided into a plurality of sections by notches, the inner edge of said doctor blade being looped, a rod provided with a longitudinal groove for receiving the looped

inner edge of said doctor blade, means securing said doctor blade in the groove of said rod, and means mounted on said housing for rocking said rod to vary the pressure of said blade against said

5 roll.

3. An inking mechanism for roll type printing presses comprising a housing provided with an ink reservoir, a plurality of rolls rotatably mounted in said housing on spaced apart fixed 10 axes, a roll carriage reciprocably mounted on said housing and movable relative thereto in a direction normal to the axes of said spaced rolls, a plurality of rolls including transfer and form rolls mounted in said carriage and adapted for 15 coaction with said first named rolls, means mounted on said carriage for moving at least one of the second named rolls axially and parallel to said first named rolls and manually controlled means for moving said carriage optionally to 20 maintain said second named rolls in adjustable pressure engagement with said first named rolls or to move said second named rolls away from the first named rolls.

4. An inking mechanism for roll type printing 25 presses comprising a housing provided with an ink reservoir, a plurality of rolls rotatably mounted in said housing on spaced apart axes, a roll carriage reciprocably mounted on said housing and movable relative thereto in a direction 30 normal to the axes of said spaced rolls, a plurality of rolls mounted in said carriage and adapted for coaction with said first named rolls, manually controlled means for adjustably positioning said roll carriage to move the rolls carried thereby toward and away from said first mentioned rolls, a vibrator roll mounted in said carriage for coacting engagement with the other rolls carried thereby, means for vibrating the vibrator roll 35 axially and parallel to the other of said rolls and means for releasing the vibrator roll from pressure contact with the coacting rolls.

5. An inking mechanism for roll type printing 40 presses comprising a housing provided with an ink reservoir, a plurality of rolls rotatably mounted in said housing on spaced apart axes, a roll carriage reciprocably mounted on said housing and movable relative thereto in a direction 45 normal to the axes of said spaced rolls, a plurality of rolls mounted in said carriage and adapted for coaction with said first named rolls, manually controlled means for adjustably positioning said roll carriage to move the rolls carried thereby toward and away from said first mentioned rolls, a vibrator roll mounted in said carriage, means 50 for continuously moving the vibrator roll axially and parallel to the other of said rolls, a pair of pivotal links mounted on said carriage for holding said vibrator roll in coacting engagement with said other rolls carried thereby, and adjusting means for moving said links relative to 55 said carriage.

6. An inking mechanism for roll type printing 60 presses comprising a housing, a plurality of rolls mounted in said housing including a fountain roll, transfer, vibrator and form rolls, means 65 mounted on said housing and driven from one of the rolls for reciprocating the vibrator rolls axially, adjustable carriage means for effecting simultaneous movement of said form and transfer rolls toward and from said fountain roll and at 70 least one of said vibrator rolls, a pair of rider rolls adapted for pressure engagement with said form roll and a movable mounting for said rider rolls to permit movement of said rolls away from 75 said form roll.

7. An inking mechanism for printing presses comprising a housing providing an ink reservoir and a communicating roll compartment into which ink from said reservoir is adapted to flow, a plurality of ink transfer rolls rotatably mounted in said housing and including a fountain roll having the surface thereof movable in the ink in said roll compartment, and movable impeller means mounted in said reservoir for accelerating the flow of ink from said reservoir to said roll compartment.

8. An inking mechanism for printing presses comprising a housing providing an ink reservoir and a communicating roll compartment into which ink from said reservoir is adapted to flow, a plurality of ink transfer rolls rotatably mounted in said housing and including a fountain roll having the surface thereof movable in the ink in said roll compartment, an impeller mounted in said reservoir for accelerating the flow of ink therefrom to said roll compartment, and operative connections between one of said rolls and said impeller.

9. A printing press comprising a frame, a plurality of printing rolls mounted on said frame, an elongated platform disposed below said rolls and provided with a plurality of transverse guideways parallel to said rolls, an inking mechanism unit comprising separate inking mechanisms including a reservoir and transfer rolls replaceably mounted in each of said guideways, and means

for moving said platform vertically to simultaneously adjust each of said inking mechanisms into and from cooperative inking position with said printing rolls.
